UNITED STATES PATENT OFFICE

ADELE SMITHLINE SIMPSON, OF NEW YORK, N. Y., ASSIGNOR TO ASSOCIATED MERCHANDISING CORPORATION, OF NEW YORK, N. Y., A CORPORATION OF NEW JERSEY

DESIGN FOR A DRESS

Application filed September 13, 1932. Serial No. 44,824. Term of patent 3½ years.

To all whom it may concern:

Be it known that I, ADELE SMITHLINE SIMPSON, a citizen of the United States, and resident of 275 Central Park West, New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.

ADELE SMITHLINE SIMPSON.
